TWO-CYCLE INTERNAL COMBUSTION ENGINE

Robert Thomann, Winterthur, Switzerland, assignor to the firm of Sulzer Freres Societe Anonyme, Winterthur, Switzerland

Application June 2, 1932, Serial No. 614,867
In Switzerland April 29, 1932

5 Claims. (Cl. 123—65)

Two-cycle internal combustion engines are known in which subdivided ports are provided for the introduction of air, the upper ports being uncovered by the piston before it covers the exhaust ports, and in which air at a lower pressure is led in through both rows of ports and also air at a higher pressure through the upper row of ports into the working space of the cylinder.

Such internal combustion engines, in which the air can flow into the working cylinder in three different ways, possess the drawback that the scavenging air can flow out too soon through the exhaust ports. The invention relates to a two-cycle internal combustion engine with the inlet ports arranged opposite the exhaust ports, with automatic members for scavenging the cylinder through air at a low pressure, and positively operated members for charging and supercharging the cylinder with air at a higher pressure, and consists in making the scavenging start suddenly and through a wide opening by merging the preexistent plurality of small ports into one single large row, so that practically the whole of the space possible to be used for inlet purposes is thereby used for the flow of scavenging air, which is also positively guided towards the cylinder cover, whereby the exhaust gases are positively and completely pushed directly out of the exhaust ports. That is to say common inlet ports, closed by the piston during the compression stroke after the exhaust ports, are provided to effectuate both the scavenging, the charging and supercharging of the cylinder, instead of the hitherto usual upper row and lower row of ports, the subsistent third path for the scavenging air being totally eliminated, for the purpose of preventing air flowing out too soon through the exhaust ports, or short-circuiting.

One example of the object of the invention is shown diagrammatically in the accompanying drawing of a single-acting vertical internal combustion engine.

The working cylinder 1 is provided with inlet ports 2 lying opposite the exhaust ports 3, which are closed before the inlet during the compression stroke by the piston 4, which is shown in the drawing at its lower dead centre. The cylinder is scavenged by air at low pressure, flowing in from the air pipe 5 which can be shut off from the working space 7 by means of automatic members 6, whilst the charging and supercharging of the working space is effected by air at a higher pressure taken from the air pipe 8 which is shut off from the working space 7 by the positively controlled members 9. The valve or valves

9 are controlled by a cam 11 mounted on the shaft 10, the cam 11 acting on a lever 12 which in its turn is connected to the valve 9 through the rod 13.

According to the invention, common inlet ports 2, closed by the piston, during the compression stroke after the exhaust ports, are provided for scavenging and charging and supercharging. These inlet ports, through which, under elimination of a third way for the scavenging air, both the air at low pressure used for scavenging the cylinder and also the air at a higher pressure for charging and supercharging is led into the cylinder, are directed towards the cover of the working space and are not reached by the piston 4 during the compression stroke until the piston has moved through a certain distance *a* of its stroke, for example at least 10%. The passage 16 provided for introducing the air is formed with a bend in order to control the flow better; that is to say, including the bend, etc., the inlet ports are defined by conduit surfaces arranged oblique to the cylinder axis and each of the surfaces being inclined at a different angle to the generatrix of the cylinder, as clearly shown in the accompanying drawing at 16, 2. More specifically, the inlet ports are cast or cored in the form of truncated, oblique cones-of-revolution, with the upper surface slanted downwardly more steeply than the lower, whereby to positively direct and control the flow and accomplish the objects postulated above. The method of working is as follows:

As soon as the piston 4 during the expansion stroke begins to uncover the exhaust ports 3, the products of combustion flow out from the working space 7 into the exhaust. After the pressure in the working space 7 has fallen to or lower than the pressure of the scavenging air in the pipe 5, the valves 6 open; the scavenging of the cylinders begins and continues until the moment where the piston 4 returning from its lower dead centre position has nearly the position 4* shown in dotted lines, i. e. shortly before the exhaust ports are covered by the piston. At this moment the valve or valves 9 are fully open (dotted position of the piston 4 and of the cam 11) and the charging and supercharging air compressed to a higher pressure than the scavenging air flows through the ports 2 into the working space 7 until the ports 2 are closed by the piston during the up-stroke. The charging and supercharging air at a higher pressure flowing into the passage 15 closes the valves 6. After the piston 5 has closed the ports 2, the valve 9 is led back to its seat

without shock under the influence of the spring 14. I claim:

1. In a two-cycle internal combustion engine, having a cylinder including outlet ports, and a single row of inlet ports situated opposite to the outlet ports for inlet of scavenging, and charging and supercharging airs, the combination with the said single row of inlet ports situated opposite to the outlet ports, of automatic members for scavenging the cylinder by air at a low pressure, and positively controlled members for charging and supercharging the cylinder with air at a higher pressure, the common row of ports for the inlet of the scavenging air, and the charging and the supercharging air, being closed by the piston during the compression stroke after the outlet ports are closed, for admitting the scavenging and charging and supercharging air to the cylinder.
2. In a two-cycle internal combustion engine having a cylinder including outlet ports, and a single row of inlet ports situated opposite to the outlet ports for inlet of scavenging, and charging and supercharging airs, the combination with the single row of inlet ports situated opposite to the outlet ports, of automatic members for scavenging the cylinder by air at a low pressure, and positively controlled members for charging and supercharging the cylinder with air at a higher pressure, the common row of ports for the inlet of the scavenging air, and the charging and the supercharging air, being closed by the piston during the compression stroke after the outlet ports are closed, for admitting the scavenging and charging and supercharging air to the cylinder, each of said inlet ports being defined by surfaces-of-revolution lying oblique to the cylinder axis.
3. In a two-cycle internal combustion engine, having a cylinder including outlet ports, and a single row of inlet ports situated opposite to the outlet ports for inlet of scavenging, and charging and supercharging airs, the combination with the single row of inlet ports situated opposite to the outlet ports, of automatic members for scavenging the cylinder by air at a low pressure, and positively controlled members for charging and supercharging the cylinder with air at a higher pressure, the common row of ports for the inlet of the scavenging, and the charging and the supercharging air, being closed by the piston during the compression stroke after the outlet ports are closed, for admitting the scavenging and charging and supercharging air to the cylinder, the inlet ports being bounded by guide surfaces arranged oblique to the cylinder axis, and one part of the surface of at least one inlet port being inclined at a different angle to the generatrix of the cylinder-wall from the rest of the surface of said port.
4. In a two-cycle internal combustion engine having a cylinder including outlet ports, and a single row of inlet ports situated opposite to the outlet ports for inlet both of scavenging, and of charging and supercharging airs in common, the combination with the said row of ports, of automatic members for scavenging the cylinder by air at a low pressure, and positively controlled members for charging and supercharging the cylinder with air at a higher pressure, the row of ports for the common inlet of the scavenging, and of the charging and the supercharging air, being closed by the piston during the compression stroke after the outlet ports are closed, for admitting the scavenging and charging and supercharging air to the cylinder, the said inlet ports being defined by the revolution of a generatrix having a greater slope toward the vertical at the top of the port than near the bottom of the port.
5. In a two-cycle internal combustion engine having a cylinder including outlet ports, and a single row of inlet ports situated opposite to the outlet ports for inlet both of scavenging, and of charging and supercharging airs in common, the combination with the said row of ports, of automatic members for scavenging the cylinder by air at a low pressure, and positively controlled members for charging and supercharging the cylinder with air at a higher pressure, the row of ports for the common inlet of the scavenging, and of the charging and the supercharging air, being closed by the piston during the compression stroke after the outlet ports are closed for admitting the scavenging and charging and supercharging air to the cylinder, each of said inlet ports being bounded by guide surfaces lying oblique to the cylinder axis.

ROBERT THOMANN.
